UNITED STATES PATENT OFFICE.

IVAR PETER BAGGER KNUDSEN, OF COPENHAGEN, DENMARK.

CENTRIFUGAL MACHINE.

No. 861,736.

Specification of Letters Patent.

Patented July 30, 1907.

Application filed September 24, 1906. Serial No. 836,022.

To all whom it may concern:

Be it known that I, IVAR PETER BAGGER KNUDSEN, director, a subject of Denmark, residing at 56 Svanemöllevej, Copenhagen, in the Kingdom of Denmark, 5 have invented new and useful Improvements in Centrifugal Machines, of which the following is a specification.

This invention relates to centrifugal apparatus where-
in the pivot of the centrifugal drum is loosely connected
10 to the driving shaft, and it has for its object to provide
a mounting for the centrifugal drum such that the drum
can freely accommodate itself to the oscillations or vi-
brations produced by the forces generated by the rota-
tion, without such oscillations etc. being transmitted to
15 the driving shaft, and, further, that the drum will have
a constant tendency to return to its normal position of
equilibrium.

By observations and experiments made in connec-
tion with supported centrifugal drums it has been as-
20 serted that, notwithstanding the presence of the actual
shaft, the drum when rotating has a tendency to
revolve round the geometrical axis in which the move-
ment of inertia is greatest, and since (in the constructions
25 heretofore employed) it is impossible to make the geo-
metrical axis coincide with the center line of the actual
or mechanical shaft, such arrangements always exhibit
great friction in the bearings, with a correspondingly
great consumption of power and wear and tear. The
30 present invention is designed to remedy this drawback
by enabling the centrifugal drum to rotate freely round
an axis situated in any position independently of the
axis of the mechanical shaft, while the arrangement is
also such that the oscillation of the drum will cause the
35 center of gravity of the drum to be raised, with the re-
sult that the drum will have a constant tendency to re-
turn to its normal position of equilibrium.

The improved construction is characterized by the
fact that the connection between the drum and the
driving shaft is effected by means of a carrier which is
40 loosely connected to the drum and which supports the
latter at a point situated some distance above its center
of gravity and is capable of oscillating about its point of
connection with the driving shaft, which point is situated
45 considerably below the said center of gravity, while the carrier, in transmitting rotary movement to the
drum, also allows free rotation of the drum about any axis of inertia outside of the axis of the carrier and in relation to which the drum has its greatest moment of inertia. It is also a condition that the bearing for
50 supporting the pivot of the drum (which bearing is ca-

pable of following the oscillation of the drum) shall have its center situated in or near the horizontal plane passing through the center of gravity of the drum. In consequence of this arrangement, the oscillations of the drum are always transmitted in only a very reduced 55 degree to the carrier, and through the latter to the driving shaft, while further, the horizontal pressures that would otherwise be transmitted from the drum through the shaft to the driving mechanism disappear altogether. The raising of the center of gravity has also 60 the result of reducing the oscillation of the axis of inertia, without this having any influence upon the light running of the centrifugal apparatus.

The accompanying drawings illustrate one form of the invention by way of example. 65

The centrifugal drum A is so formed that the sup-
porting bearing B of the pivot C may be placed at such
a height as to allow of its center being situated in or
near the horizontal plane passing through the center of
gravity c of the drum, while at the same time the drum 70 is supported by a carrier E at a point some distance
above its center of gravity. The motion is transmitted
from the driving shaft D to the pivot C by means of this
carrier E which is loosely connected to both. In the
example illustrated the carrier is in the form of a shaft 75 the two ends of which engage with cross pins a and b or
with trunnions provided on the pivot C and the driving
shaft D. In consequence of this arrangement, by rea-
son of the mobility of the supporting bearing and also
by reason of the fact that the pivot is only loosely con- 80 nected to the carrier shaft E, the drum is enabled to
follow freely in all direction the movements which are
produced by the vibration and oscillation that occur
during the rotation, yet without such movements be-
ing transmitted to the driving shaft. At the same time 85 the drum, in consequence of its point of support being
situated above the center of gravity of the drum, will
have a constant tendency to return to its normal posi-
tion of equilibrium. This will be obvious from the
drawing which shows that the drum rises when moved 90 out of its normal position of equilibrium; if, for exam-
ple, the drum moves into the position A¹, its pivot will
assume the position C¹, its supporting bearing will
move to the position B¹, and the carrier shaft will as-
sume the position E¹. Consequently the drum will 95 have been raised so that its center of gravity is now
situated at c¹, while the distance a¹ c¹ must always be
equal to the distance a, c.

Having now particularly described and ascertained
the nature of the said invention and in what manner 100

the same is to be performed. I declare that what I claim is.

In a centrifugal machine, the combination of a vertical shaft, a drum oscillatably mounted on the upper end of said shaft to be rotated thereby and supported by the shaft some distance above the center of gravity of the drum, a driving shaft to which the lower end of the vertical shaft is oscillatably connected at a point considerably below the center of gravity of the drum, a pivot fixed on the drum,

and an oscillatory bearing for said pivot having its center located substantially in a plane passing through the center of gravity of the drum.

In testimony whereof I have signed my name to this specification in the presence of two subscribing witnesses.

IVAR PETER BAGGER KNUDSEN.
